SHEARING MACHINES

August Sturtzer, Dusseldorf, Germany, assignor to Schloemann Aktiengesellschaft, Dusseldorf, Germany

Application May 17, 1954; Serial No. 430,322

Claims priority, application Germany May 21, 1953

3 Claims. (Cl. 164—47)

Ingot-shearing machines are known to the upper blade-holder of which is pivoted a lever, which, driven by a stationary crank shaft, executes reciprocating swivelling movements. The lever is then able to raise the lower blade-holder, which can swivel about a stationary axis, through the medium of a tension member. This stationary axis may coincide with the axis of the crank shaft. These ingot shears are preferably operated by a reversible method. In them only the upper blade-holder is fixedly adjusted by means of a manually actuated spindle or the like, and the tension member is attached with an elongated hole to a pin on the lower blade-holder. This construction has the disadvantage that will be gathered from the following description of a known constructional example illustrated in Figure 5. The invention itself is illustrated by Figures 1 to 4.

In the known ingot-shearing machine shown in Figure 5 the upper blade-holder 1 is fixedly adjustable by means of a spindle 2. On the upper blade-holder 1 a lever 4 can rock about a pivot 3, the lever 4 being movable by a crank 6, which is mounted on a shaft 5. The crank 6 is attached by way of connecting-rod 7 to the lever 4. In reversing operation, that is, when the shaft 5 is reciprocated in such a way that the crank 6 is rotated from the position shown through the upper dead centre into the corresponding left-hand position, and from here is rotated back again upon the same path, the lower blade-holder 8 is lifted each time from its support, since a rod 10, provided with a slot 11, raises the lower blade-holder. Therefore the cut is effected by raising the lower blade 12, while the upper blade remains stationary. Such shears have the advantage that the stroke of the lower blade can be adjusted to the height of the ingot 13 to be cut, so that the lower blade does not have to execute any idle travel. Now the ingots to be cut mostly have however a thick head. In order to be able to slide this head through between the upper and lower blades, the throat aperture shown in Figure 5 is not sufficient. Hence for the pushing through the head of the ingot the upper blade-holder 1 has to be adjusted upwards every time by hand by means of the spindle 2, while the crank 6 is rotated into the lower dead centre. Since this is very complicated, the upper blade-holder 1 is in operation usually located so high up that all ingots, even those with the thickest heads, can be slid into the throat aperture. In this way the advantage that the shears described are intended to present is to a great extent lost, for a long idle path now has to be traversed for every cut.

Now the object of this invention is to obviate the said disadvantages, and the invention consists in the feature that the upper blade-holder is freely displaceable in a vertical direction, and in its downward movement strikes against an abutment, and that the tension member is rigid and is undisplaceably pivoted to the lower blade-holder and to a lever which is rockable on the upper blade-holder. The abutment for the upper blade-holder may advantageously be adjustable, so that the shearing

2

machine can be adjusted for different thicknesses of the ingots and ingot heads.

The invention is illustrated in Figures 1 to 4 of the drawing, in which:

5 Figure 1 shows the shears in the position with the maximum throat aperture;

Figure 2 shows the shears after the ingot head has slid through at the beginning of the cutting work;

10 Figure 3 shows the shears at the termination of the cut; and

Figure 4 shows the shears with a throat aperture which is not so large as the thickness of the ingot, and permits the displacement of the ingot for the next cut.

Figure 5 shows an old and well known construction.

15 The upper blade-holder 1a is slidably supported on a corresponding support 20. An abutment 21, which is adjustable with the aid of the spindle 2a, limits the travel of the upper blade-holder 1a in a downward direction. At 3a is pivoted the lever 4a, which is rocked up and down by the connecting rod 7a as soon as the crank 6a, which is rotatable with the undisplaceable crank shaft 5a, is rotated in a counter-clockwise direction. The lever 4a is connected with the lower blade-holder 8a through a link 10a, which is pivoted to the lever 4a and to the 20 lower blade-holder 8a on stationary pivots, without possessing here the longitudinal slot 11 shown in Figure 5. The lower blade-holder 8a rests upon the support 9a, and is pivoted on the machine frame by means of the shaft 5a.

25 Figure 1 shows the shearing machine in the position with the greatest width of throat. In this position the 30 ingot with its thick head is slid into the shearing machine. Thereupon the shaft 5a is rotated right into about the position of Figure 2, wherein the lever 4a turns about the pivot 22, and the upper blade-holder descends until it 35 comes into contact with the abutment 21. In this position the cut begins, since the link 10a now raises the lower blade-holder 8a, after the upper blade-holder 1a has struck against the stop 21 and can no longer move any further downwards. In the position according to Figure 3 the 40 cut is terminated, since the lower blade-holder 8a here assumes its highest position. In the position according to Figure 4 the throat of the shears is opened again so far that the ingot can be slid further on, the throat not being opened any more than is necessary for the further 45 advance of the ingot. If the shaft 5a is now turned back in reversing operation in a clockwise direction, a fresh cut begins, since the shears then pass directly into the position shown in Figure 3. When they thereupon 50 reach the position shown in Figure 2 the throat has reopened by the height that is necessary for the further advance of the ingot. The further operation of the shearing machine for cutting off individual sections from the ingot is therefore effected in reversing operation, the shears rocking to and fro between the positions of Figures 2 and 4, and the crank 6a always being moved over the 55 upper dead centre.

Only when a fresh ingot with a thick head is to be inserted will the shears be brought once into the position of Figure 1, for the purpose of inserting the head. Under 60 these circumstances the throat opens, by raising the upper blade-holder 1a, so far that the head can be slid through.

The shearing machine according to the invention can therefore be opened, simply by controlling the shaft 5a, to such an extent that the thick ingot head can be inserted, whereas the cutting is effected in reversing operation merely by controlling the shaft 5a between the positions shown in Figures 2, 3 and 4.

65 The adjusting of the abutment 21 is only required when changing to ingots of different dimensions.

I claim:

70 1. An ingot-shearing machine, comprising: a machine frame, an upper blade-holder vertically movable in the

machine frame, a lower blade-holder pivotally mounted by its rear end on the machine frame, a lever pivotally mounted by its front end on the upper blade-holder, a shaft journalled in the machine frame, a crank mounted fast on the shaft, a connecting-rod connecting the crank-pin of the said crank to the rear end of the lever mounted on the upper blade-holder, a rigid link pivotally connecting an intermediate point of the same lever to an intermediate point of the lower blade-holder, a fixed abutment on the machine frame on which the lower blade-holder rests during the opening movement of the shears, an adjustable abutment on the machine frame adapted to stop the descent of the upper blade-holder when the rotation of the crank shaft raises the rear end of the lever, thus causing the link to pull up the lower blade-holder so as to

execute the cut, and means for rotating the shaft to and fro about its upper dead-centre position, in which the throat of the shears is closed.

5 2. An ingot-shearing machine as claimed in claim 1, further comprising means for rotating the shaft into a lower dead-centre position, in which the throat opening is wide enough to accommodate the head of an ingot.

10 3. An ingot-shearing machine as claimed in claim 2, the said link being undisplaceably pivoted to the lower blade-holder and to the lever pivoted to the upper blade-holder.
